RADIATOR

John T. Bryce, Park Ridge, Ill.

Application December 4, 1946, Serial No. 713,988

1 Claim. (Cl. 257—133)

1

The invention relates to improvements in radiators and more particularly to radiators of the type adapted to be mounted on the side walls of a room adjacent the floor in place of the usual baseboard.

One object of the invention is to provide a radiator of the above general character which is more efficient and less bulky than conventional cast iron radiators and which lends itself readily to production by low cost manufacturing operations.

A more specific object is to provide a baseboard radiator having a main body portion constructed to provide efficient circulation of the heating fluid and so shaped that it can be manufactured from metals such as aluminum or its alloys by an extrusion process.

Another object is to provide a baseboard radiator which is easy to install and which requires no special cutting of the wall studding, floor or associated parts of the building structure.

A further object is to provide an improved baseboard radiator adapted to be constructed in sections which may be assembled in varying groups to meet the individual heat transfer requirements of different installations and which when installed is easy to keep clean and presents an attractive appearance.

It is also an object of the invention to provide an improved method of constructing radiators of the baseboard type which materially reduces costs and which produces a more efficient and practical radiator than has been available heretofore.

Other objects and advantages of the invention will become apparent from the following detailed description of the preferred embodiments illustrated in the accompanying drawing, in which:

Figure 1 is a fragmentary perspective view of a baseboard radiator embodying the features of the invention showing the manner in which it is installed, the radiator being shown partly in section.

Fig. 2 is a front elevational view of the radiator with a portion of the front wall broken away to show the interior construction.

Fig. 3 is a transverse sectional view of the radiator taken in a vertical plane substantially on the line 3—3 of Fig. 2.

Fig. 4 is a sectionalized front view of a modified form of the radiator.

Fig. 5 is a sectional view taken in a vertical plane substantially on the line 5—5 of Fig. 4.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

2

For purposes of illustration, the improved radiator has been shown in a form particularly suitable for installation in homes, office buildings and similar structures that ordinarily have wooden baseboards extending along the side walls adjacent the floor. Preferably, the radiator is made to simulate a baseboard, being of substantial width but relatively thin so as to be inconspicuous and yet present a maximum area of radiating surface. For convenience of installation the radiator is made in sections of suitable lengths which may be assembled in varying combinations to fit rooms of different sizes. Dummy sections, similar in external appearance to the regular heating sections, may also be provided so that uniformity of appearance may be maintained in installations where the overall length of the baseboard is greater than is required to provide the necessary radiating surface.

Referring to Figs. 1-3 of the drawings, the improved radiator in its preferred form is constructed from an elongated metal casing 10 having spaced parallel front and back walls 11 and 12 connected by relatively narrow top and bottom walls 13 and 14. A partitioning member or wall 15 located intermediate the top and bottom walls divides the interior of the casing into parallel upper and lower passages 16 and 17 extending longitudinally of the casing. To facilitate installation, the rear wall 12 is arranged to project above the top wall 13, providing a narrow ledge or flange 18 extending along the upper edge of the casing, and the bottom wall 14 is set inwardly from the lower edges of the front and back walls 11 and 12 to form a downwardly opening channel 19 at the bottom of the casing.

In the finished radiator the casing 10 is closed at opposite ends by end plates 20 and 21 which may be welded or brazed in place to seal the casing against leakage. At one end of the casing, the partitioning member 15 is cut away sufficiently to provide clearance so that the plate 20 may be set in from the end of the casing, but in abutting relation to the partitioning member, as shown at the left end of the casing in Fig. 2. At the other end of the casing, the partitioning member 15 is cut back a substantial distance inwardly of the end plate to provide a transverse passage 22 connecting the longitudinal passages 16 and 17, which thus form a single heating fluid flow channel extending longitudinally along the lower portion of the casing and then back along the upper portion of the casing. Openings 23 and 24 in the back wall 12 communicate respectively with the passages 16 and 17 adjacent their closed ends to provide inlet and outlet ports for the channel. Connections with the heating system or with adjacent radiator sections may be made by means of suitable pipes or tubular elbow fittings 25 and 26 brazed or welded to the casing. The holes 23 and 24 are preferably spaced apart longitudinally of the casing to permit the inlet

and outlet pipes to extend vertically through the studding without interference.

It will be observed that the walls of the casing 10, including the partitioning wall, are all disposed in planes parallel to the longitudinal axis of the casing and that there are no lateral projections of any kind. This construction permits the casing to be produced by an extrusion process from metals such as aluminum or aluminum alloys. In the manufacture of the radiator, the extruded casing member is cut to the required size and the ends of the partitioning wall 15 are milled out to provide the necessary set back for the end plates 20.

The use of light weight metals of the above type is particularly advantageous in radiators because of their excellent heat conducting properties materially reducing the size of the radiator required for effectively heating a given space. Moreover, radiators so constructed are light in weight and therefore easy to handle and install. The light weight character of the radiator is a further advantage, as the cost of extruded shapes is ordinarily figured on the basis of weight. It has been found that in spite of the higher cost of the basic material, radiators utilizing light weight extruded shapes of the type above described may be produced more cheaply than conventional cast iron radiators and they are much more efficient than the latter.

To enable the improved radiator to be fitted into rooms of different sizes and to permit required variations of the radiating surface provided, the radiator is preferably constructed in sections of different lengths, each section providing a complete circulating system or channel for the heating fluid. The number of sections required to provide the necessary radiating surface are then assembled in end-to-end relation and suitably interconnected with each other and with the heating system by way of the inlet and outlet ports 23 and 24. Where the length of the radiator required for a room is less than the total baseboard length, sufficient dummy sections are inserted to complete the baseboard. Alternatively, the regular radiator sections may be installed, but left unconnected with the heating system.

The manner in which the improved radiator is installed in a room having a side wall 27 and a floor 28 will be readily seen by reference to Figs. 1 and 3 of the drawings. To locate the lower edge of the radiator, a thin, flat locating strip 29 adapted to fit snugly in the channel 19 of the radiator casing is nailed to the floor in proper spaced relation to the wall. The radiator is then placed over the locating strip, as shown in Fig. 1, and the upper edge is secured in place by a mounting strip 30 rabbeted at its lower edge to receive the flange 18 at the top of the casing. The mounting strip may be secured to the wall studding in any suitable manner, as by screws 31. The upper portion 32 of the front wall 11 may be sloped inwardly so as to underlie the mounting strip 30 and thus avoid the formation of a dust collecting ledge, making it easy to keep the radiator in a clean and sanitary condition. A quarter round finishing strip 33 fastened to the floor 28 conceals the lower edge of the radiator and covers any gaps that may result from irregularities in the floor surface. Installation may thus be effected quickly and easily with a minimum of labor. Only two relatively small holes need be cut in the wall for each radiator

section and these may be made with an ordinary drill.

In cases where it is necessary or desirable to lead the connections to the radiator sections through the floor instead of through the wall, the construction of the radiator is modified as shown in Figs. 4 and 5. The body of the radiator is formed from a section of the casing 10 above described, but in this instance the partitioning member is cut away a substantial distance inwardly of each of the end plates 20 and 21, thus connecting the longitudinal passages 16 and 17 at both ends. One end of the passage 17 is then closed by an upright auxiliary partitioning plate 35 welded or brazed in place between the bottom wall 14 of the casing and the adjacent end of the partitioning member 15. In this way a single continuous flow channel is provided which extends upwardly at one end of the casing, thence longitudinally through the upper portion of the casing and back through the lower portion to the partition 35. Openings 36 and 37 are provided in the bottom wall 14 of the casing for the connection of suitable pipes or fittings 38 and 39 to the opposite ends of the channel for the circulation of the heating fluid therethrough. Installation of the modified form of radiator is effected in the manner heretofore described, except that in this case the holes for the inlet and outlet pipes are drilled in the floor instead in the wall.

It will be apparent from the foregoing that the invention provides a baseboard radiator of novel and advantageous construction. The radiator utilizes in its construction a casing section which by reason of its novel shape may be produced efficiently and cheaply by an extrusion process. Light weight metals having good heat conducting properties may thus be used for the radiator with substantial improvements in its heat transfer efficiency and with a substantial reduction in the size required to heat a given space. Moreover the improved radiator is easy to handle and install and very attractive in appearance.

45 I claim as my invention:

A baseboard radiator comprising an elongated hollow casing having relatively wide front and back walls and substantially narrow top and bottom walls, end plates closing the ends of said casing, a partitioning member dividing said casing into two parallel passages extending longitudinally of the casing, said partitioning member terminating inwardly from each of said end plates, and an auxiliary partitioning member closing one end of the lower passage, said bottom wall having a pair of openings disposed on opposite sides of said auxiliary partitioning member providing an inlet and an outlet at opposite ends of the channel formed by the two connected passages.

JOHN T. BRYCE.
